BOTTLE CAPPING MACHINE

Benjamin F. Davis, Minneapolis, and Walter H.
Riedel, White Bear Lake, Minn.Application December 26, 1930
Serial No. 504,716

25 Claims. (Cl. 226—92)

This invention relates to bottle capping machines and is particularly designed as an improvement on the machine for the above as disclosed and claimed in the Benjamin F. Davis application for United States Letters Patent of the same title, filed May 28, 1930 under Serial Number 456,442.

In said prior machine and the present machine the same are designed for forming a cap, especially for milk and cream bottles, of the type having a depressed central portion and a sanitary marginal flange arranged to extend outward over the rim of the neck of a bottle to which it is applied and covers the same and in applying the formed cap to a bottle.

In the prior machine, however, caps are formed and discharged whether or not there is a bottle positioned to be capped, thus causing a large number of caps to be wasted for the reason that there is necessarily more or less interruption in the feeding of bottles to the machine while the action thereof is continuous.

Our present invention is directed to the formation of a cap and its discharge, only when a bottle is positioned to be capped, thus preventing waste. Said invention is further directed to the straight line feeding of cap blanks to cap forming dies and from said dies to a cap applying device and other important objects, as will hereinafter appear.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view in side elevation of twin cap forming and bottle capping heads applied to the reciprocating vertical shaft and guide posts of a bottle filling machine;

Fig. 2 is a view corresponding to Fig. 1 with the exception that the twin heads are in bottle capping position, some parts being diagrammatically illustrated by means of broken lines;

Fig. 3 is a view partly in side elevation and partly in central vertical section taken on the line 3—3 of Fig. 5, with the parts positioned as shown in Fig. 1;

Fig. 4 is a view corresponding to Fig. 3 but showing the parts positioned as shown in Fig. 2;

Fig. 5 is a view partly in plan and partly in horizontal section taken on the line 5—5 of Figs. 2 and 4;

Fig. 6 is a fragmentary detail view of the cap forming dies and capping device positioned, as shown in Figs. 1 and 3;

Fig. 7 is a view corresponding to Fig. 6 but

showing the parts positioned as shown in Figs. 2 and 4;

Fig. 8 is a fragmentary detail view showing the driven crank for reciprocating the vertical shaft of the bottle capping machine;

Fig. 9 is a perspective view of the frame for the twin heads on a reduced scale;

Fig. 10 is a perspective view of one of the heads with certain parts removed;

Fig. 11 is a fragmentary perspective view of the operating mechanism for one of the movable dies;

Fig. 12 is a fragmentary bottom perspective view of one of the capping heads shown in Fig. 10;

Fig. 13 is a fragmentary detail view in section taken on the line 13—13 of Fig. 3, on an enlarged scale;

Fig. 14 is a perspective view of one of the cap applying plungers;

Fig. 15 is a detail view in section taken on the line 15—15 of Fig. 5;

Fig. 16 is a fragmentary detail view with some parts sectioned on the line 16—16 of Fig. 5; and

Fig. 17 is a side elevation of the parts shown in Fig. 16.

The present invention may be designed as an individual cap forming and bottle capping machine or it may be embodied in a bottle filling machine, as illustrated, and wherein the twin bottle capping heads of the commercial machine are removed and the machine of this invention substituted therefore.

Of the parts of the commercial bottle filling machine shown, certain of which are only diagrammatically illustrated, it is important to note the feed table 20, vertical movable shaft 21 and a pair of fixed upright guide posts 22. Said guide posts 22, which extend upright through the feed table 20, are connected by upper and lower tie members 23 which have split clamping collars 24 through which the guide posts 22 extend and said collars frictionally clamp thereon.

The shaft 21, which is midway between the guide posts 22 and parallel thereto, is mounted for endwise reciprocating movement in bearings 25 formed with the tie members 23 intermediate of their ends. The shaft 21 is reciprocated from a driven shaft 26 under the table 20 by a crank 27 thereon and connected by a link 28 to the lower end of said shaft 21, see Fig. 8.

A cross-head 29 is slidably mounted on the guide posts 22 and has a recessed seat 30 for a twin capping head, not shown, secured by a pair of nut-equipped bolts 31 to said cross-head. This cross-head 29 is secured to the shaft 21 for relative longitudinal adjustment by a long screw-rod 32, the upper end of which is turnably mounted in a bearing bracket 33 on the upper end of said shaft, held thereby against

75

endwise movement and having screw-threaded engagement with a nut-acting member 34 on the back of said cross-head. A hand-crank 35 on the upper end of the screw-rod 32 is provided for rotating the same to raise or lower the cross-head 29.

Milk or cream bottles X are successively moved onto the feed table to bottle filling positions and thereafter are moved to bottle capping positions by well-known mechanism which, for the purpose of this case, it will not be necessary to illustrate. From a broad viewpoint the bottles X may be placed on the table 20 in bottle capping positions by hand or otherwise.

Referring now in detail to the invention which includes twin capping heads that are laterally spaced and each thereof includes a base 36 on which is bolted a block 37 having formed therein a front cylindrical magazine 38, a center or intermediate die cylinder 39, and a rear cap applying cylinder 40. The axes of the magazine 38 and the two cylinders 39 and 40 are all in the same vertical plane and the planes of the two heads are parallel. On the sides of each block 37 is a pair of upright guide bars 41 located at diametrically opposite points from the axis of the cap applying cylinder 40. These guide bars 41 are equipped with anti-friction rollers 42 and mounted in channel-shaped ways 43 formed with a frame 44. This frame 44, at its back, is fitted in the seat 30 and rigidly secured by the bolts 31 to the cross-head 29.

Normally each head is connected by lock mechanism to the frame 44, for common reciprocatory movement therewith under the action of the shaft 21. This mechanism includes a pair of bell-cranks 45 the short horizontally disposed arms thereof being equipped with laterally offset rollers 46 that extend into open horizontal lock notches 47 in the walls of the frame 44 at the front thereof. These bell-cranks 45 are automatic in their action and perform another important function, as will presently appear.

As the action of each capping head is identical, the one with the other, it is thought that the description of the one will suffice for the other. The magazine 38 is designed to hold a stack of cap blanks Y which rest on the base 36 and which magazine has formed in its front wall a vertical slot which extends from the top nearly to the bottom thereof and affords a sight and finger opening 48. The lowermost blanks Y are successively moved edgewise from the magazine 38 through a passageway 49, in the wall of the block 37 between said magazine and the die cylinder 39, and into a cap forming position in said cylinder by an ejector slide 50. This ejector slide 50 is in the form of a flat plate secured to a block 51 slidably mounted in a way 52 in the base 36 and has in its inner end a segmental notch 53 of substantially the same diameter as the cap blanks Y.

Normally the ejector slide 50 is projected and the stack of cap blanks Y rest thereon, see Fig. 3. The ejector slide 50 is reciprocated by the bell-cranks 45 which are connected thereto by a pair of long links 54 to the long depending arms of said bell-cranks. The links 54 are connected to the block 51 by a pin 55 which extends through short horizontal slots 56 in a pair of depending bearing lugs 57 on the sliding block 51, see Figs. 15, 16 and 17.

A collar 58, applied to the stop pin 55 between the bearing lugs 57, is provided with

a radial stud 59 which extends rearward through a hole in a depending stop lug 60 on the sliding block 51. Encircling the radial stud 59 is a coiled spring 61 compressed between the collar 58 and stop lug 60 and yieldingly holds the sliding block 51, when the ejector slide is retracted, pressed away from the bell-cranks 45 with the bearing lugs 57 at the inner ends of the stops 56 against the stop pin 55.

A stop plate 62 on the base 36 which extends across the outer open end of the way 52 limits the retracting movement of the ejector slide 50 and positions the same with the center of its segmental notch 53 substantially at the axis of the stack of cap blanks Y, see Fig. 5. At the time the sliding block 51 engages the positive stop plate 62 the links 54 have a still further movement which compresses the spring 61 and permits the pin 55 to move in respect to the slide 56 to compensate for the movement.

The cap blanks Y are formed by a pair of cooperating dies 63 and 64 into caps Z. Each cap Z has a depressed central portion, which forms the cap proper and rests on the seat therefore in the neck of the bottle, an annular upstanding wall and an outstanding sanitary flange which extends over the outer end of the neck of the bottle X and covers the same.

The lower die 64 includes a fixed ring 65 removably mounted in a seat therefore in the top of the base 36 and a receding annular block 66 within said ring and having at its axis a depending stem 67 which works through a hole in the base 36. On the lower end of the stem 67 is a head 68 arranged to engage the bottom of the base 36 and limit the lifting movement of the block 66 in the ring 65 by a coiled spring 69. This spring 69 encircling the stem 67 is compressed between the base 36 and block 66 and normally and yieldingly holds said block 66 raised with the heads 68 in engagement with the base 36. It will be noted that the face of the lower die 64 is in the plane of the upper face of the base 36 on which the stack of cap blanks Y rest so that the lowermost cap blank Y has a direct sliding movement by the ejector slide 50 from the magazine 38 to the die cylinder 39.

The upper die 63, as shown, is in the form of a plunger mounted in the die cylinder 39 and its lower end is positioned for cooperation with the lower die 64 to form a cap Z, as shown in Fig. 7.

A stripper for removing a formed cap Z from the upper die 63 during its retracting movement is in the form of a spring-projected plunger 70 mounted in a recess in said die at the axis thereof and normally projects outward of its face.

A pair of upstanding positioning pins 71 anchored to the die ring 65 axially centers a cap blank Y thereon as the same is fed by the ejector slide 50 from the magazine 38 to the die cylinder 39, see Figs. 5 and 6. These positioning pins are located on opposite sides of the center line of travel of a cap blank Y to the dies 63 and 64 and forward of the center of said dies. The distance between the positioning pins 71 is slightly less than the diameter of a cap blank Y so that during the movement of said blank to the dies 63 and 64 the same is pinched between the positioning pins 71 and frictionally held thereby to prevent said blank from following the ejector slide 50 during its retracting movement.

In the under side of the base 36, in axial alignment with the cap applying cylinder 40, is a cap passageway 72, below said passageway is a downwardly diverging bottle centering surface 73 and at the top of said surface is an annular stop shoulder 74 arranged to engage the top of a bottle positioned thereunder to hold the capping head against further downward movement and support the same, see Fig. 4.

10 By manipulating the screw-rod 32 the capping head may be positioned, at will, for bottles of different heights. During the downward movement of the capping head by the shaft 21 the centering surface 73 first engages a positioned bottle and centers the same, if out of center, and thereafter the shoulder 74 engages the top of said bottle, stops further downward movement of the head and supports the same on the bottle which becomes a base of resistance 20 therefore.

As previously stated, when the capping head is raised, as shown in Figs. 1 and 3, said head is connected to the frame 44 for common movement therewith by the pairs of lock elements 25 45, 46 and 47, the ejector slide 50 is projected and the stack of cap blanks Y rest thereon, a cap blank Y is on the lower die 64 and a cap Z is in the cap applying cylinder 40, see Figs. 1 and 3. It is important to note that the frame 30 44 at each lock notch 47 is provided with a vertical cam surface 75 which projects upward from said notch and with a horizontal trip shoulder 76 that projects outward from the lower side of said notch, see Fig. 1. When the cam 35 rollers 46 are in the lock notches 47 the axes of said rollers are substantially in the plane of the cam surfaces 75 and the trip shoulders 76 project outward of said rollers.

At the time the downward movement of the capping head is stopped by the engagement of its stop shoulder 74 with a top of a bottle, the downward movement of the frame 44 is continued by the shaft 21 which causes the frame 44, at the lower ends of the cam surfaces 75, to engage the rollers 46 and swing the bell-cranks 45 from their positions, shown in Fig. 1, into their positions, shown in Fig. 2. This swinging movement of the bell-cranks 45 carry the cam rollers 46 out of the lock notches 47 and cause said rollers to be engaged by the cam surfaces 75 which hold the same as positioned in Fig. 2. This movement of the bell-cranks 45, acting through the links 54, retract the ejector slide 50 from under the stack of cap blanks Y and allows said stack to drop onto the base 36 and thereby position the lowermost of said blanks in the notch 53 of said slide.

The following connections are provided for projecting the movable die 63 for cooperation 60 with the fixed die 64 to form the cap Z, after the downward movement of the capping head has been stopped by a bottle positioned to be capped and during further downward movement of the frame 44, in respect to said head, to wit: 65 A pair of laterally spaced bell-cranks 77 is mounted between a pair of upright ears 78 on the block 37 and rigidly secured at their apexes to a rock-shaft 79 turnably mounted in said ears, see Figs. 3 and 11. The long arms of the 70 bell-cranks 77 are connected by a longitudinally adjustable link 80 to the horizontal or top member of a two-part T-post 81 on the frame 44 between the inner ways 43 of the two pairs, see Fig. 9.

75 A short heavy bifurcated plunger-acting arm

82 is pivoted to and between the short arms of the bell-cranks 77 for action on the movable die 63. The connection between the arm 82 and the die 63 is loose and includes a relatively large anti-friction roller 83 journaled to and between the prongs of said arm and a relatively small anti-friction roller 84 journaled to and between a pair of upstanding bearing lugs 85 on a heavy screw-plug 86 in the top of the die 63 at the axis thereof. It will be noted that the long arms of the bell-cranks 77 and the link 80 and the short arms of said bell-cranks and the arm 82 form reversely acting compound toggle levers 87 and 88, respectively. By turning the screw-plug 86 in the die 63 the projecting movement of the die 63 by the toggle levers 87 and 88 may be varied, at will, to adjust the die 63 in respect to the die 64 for wear and different thicknesses of cap blanks Y.

85 A transverse horizontal guide bar 89 is provided for directing the roller 83 downward on the roller 84 and which bar is rigidly secured to the bearing lugs 85 above the roller 84 and in front of the roller 83, see Fig. 3. The end portions of the guide bar 89 work in vertical slots 90 in the ears 78, hold the screw-plug 86 from turning in the die 63 and always keep the roller 84 properly positioned in respect to the roller 83. This guide bar 89 also takes end thrusts of the arm 82 during straightening of the toggle 95 lever 88 to prevent pressure on the die 63 that would tend to cause the same to bind in the die cylinder 39. A coiled spring 91 attached at one end to the rock-shaft 79 and at its other end to the guide bar 89 is provided for retracting 100 the movable die 63 and holding the same retracted, as will presently appear. The bar 89, is, in the particular example illustrated, preferably, removably secured to the ears 85, as by machine screws, to permit the hereinbefore- 105 described adjustment of plug 86.

110 Normally the arm 82 is yieldingly held with its roller 83 above the roller 84 and slightly out of contact therewith by a transverse bar 92 and a pair of cooperating flat springs 93. This bar 92 is loosely mounted at its end portions on a pair of horizontal headed studs 94 anchored to the ears 78 at their inner upright edges and the 115 springs 93, which are upright, are anchored at their lower ends to the block 37 and their upper end portions bear against the bar 93 near the ends thereof and normally hold the same pressed against said ears and with the arm 82 resting thereon, see Figs. 3 and 10.

120 Normally the toggle levers 87 and 88 are buckled and are straightened to project the movable die 63 during the downward movement of the frame 44 by the shaft 21 after the downward movement of the head has been stopped by a bottle in capping position. During the 125 straightening movement of the toggle lever 88 the roller 83 engages the guide bar 89 and is directed thereby downward onto the roller 84 and during the final straightening movement of said toggle lever which produces the final squeeze 130 between the dies 63 and 64 to form the cap Z the pivot between the bell-crank 77 and arm 82 moves beyond dead center and causes the roller 83 to slip from the roller 84 and thereby limit the projecting movement of the die 63.

135 During the projecting movement of the die 63 the spring 91 is placed under tension and when the roller 83 slips from the roller 84 said spring retracts the die 63. At the time the roller 83 slips from the roller 84 the arm 82 is moved 140 145

80

135

140

145

150

outward thereby, engages the bar 92, presses the same outward and thereby places the springs 93 under tension and is held back of the roller 84. During the upward movement of the frame 44 and prior to the upward movement of the capping head the toggle levers 87 and 88 are buckled by the movement of said frame in respect to said head. This buckling movement of the toggle levers 87 lift the roller 83 above the roller 84 and at which time the tensioned springs 93 swings the arm 82 into a position, as shown in Fig. 3.

While the spring 91 has sufficient tension to retract the movable die 63 it is desirable to have positive means for separating said die from the fixed die with a formed cap therebetween and which means, as shown, includes a pair of horizontally disposed bent levers 95. These levers 95 extend transversely under the end portions of the guide bar 89 outward of the ears 78, are fulcrumed at their forward ends to said ears and their inner ends are connected by links 96 to the pivot connecting the members of the toggle lever 87.

Adjustable abutments 97 on the levers 95 are provided for directly engaging the guide bar 89, see Figs. 1 and 2. These abutments 97, as shown, are in the form of a screw having threaded engagement with the levers 95 and impinge against the under side of said bar. Normally the abutments 97 are out of contact with the guide bar 89 and during the projecting movement of the movable die 63 the buckling movement of the toggle lever 87 moves the levers 95 in advance of the downwardly moving guide bar 89 and positions the abutments 97 slightly below said bar when the die 63 is in a cap forming position.

During the initial upward movement of the frame 44, the straightening of the toggle lever 87 lifts the levers 95, carries the abutments 97 into contact with the guide bar 89, and thereby imparts the initial lifting movement to the movable die 63 and separates the same from the fixed die 64 and thereafter the tensioned spring 91 completes the return movement of said movable die.

During the lifting movement of the frame 44 the cam surfaces 75 move out of contact with the rollers 46 and at which time the trip shoulders 76 engage said rollers move the bell-cranks 45 on their fulcrums in a direction to swing their long arms toward the guide posts 22. This movement of the bell-cranks 45 through the links 54 project the ejector slide 50 which moves the cap blank Y in its notch 53 endwise through the passageway 49 into the die cylinder 39 and against the positioning pins 71. At the same time the formed cap Z in the die cylinder 39 is moved edgewise from the fixed die 64 through a passageway 98, in the wall of the block 37 between the die cylinder 39 and cap applying cylinder 40, and into the cylinder 40 where the same is centered for application to a bottle positioned thereunder.

To support a cap Z in the cylinder 40 there is formed in the block 37 a pair of shallow grooves 99 which extend through said passageway and into the cylinder 40 to substantially the center thereof at diametrically opposite points. The walls of these grooves 99, which are very shallow, extend into the cylinder 40 and support a cap Z at diametrically opposite points on its flange and for a very short distance, see Fig. 13.

By reference to Fig. 3 it will be noted that the diameter of the lower portion of the cylinder 40 in which the grooves 99 are formed, is slightly larger than that of the major portion of said cylinder so that the sides of said grooves do not extend beyond the internal face of said major portion of the cylinder 40.

A cap Z in the cylinder 40 supported in the grooves 99 is applied to a bottle positioned thereunder by means of a plunger 100 mounted in the cylinder 40. The lower end of the plunger 100 is shaped to enter the depressed central portion of a cap Z and press the same onto the seat therefore in the bottle. Said plunger is further provided with an overhanging annular shoulder that engages the flange of the cap Z and presses the same onto the top of the bottle, see Fig. 3.

The plunger 100 is provided with an upstanding stem 101 which works through aligned openings in the top of the cylinder 40 and in the top member of the post 81. A stop collar 102 on the upper end of the stem 101 by its engagement with the top member of the post 81 limits the downward movement of the plunger 100 and normally supports the same therefrom. Encircling the stem 101 is a coiled spring 103 compressed between a collar 104 on said stem and the top member of the post 81 and normally holds the plunger 100 projected.

To prevent an applied cap from being lifted by suction from a capped bottle during the retracting movement of the plunger 100 diametrically extended air grooves 105 are formed in the bottom of said plunger, see Fig. 14.

Simultaneously with the moving of a cap blank Y by the ejector slide 50 from the cylinder 38 to the die cylinder 39 the formed cap Z in the die cylinder 39 is moved through the passageway 98 and into the cap applying cylinder 40 by a horizontal ejector blade 106 which extends transversely of the direction of travel of the ejector slide 50. This ejector blade 106 is mounted in the transverse portion of a U-frame 107 on the ejector slide 50, extends forward 120 thereof, and holds the ejector blade 106 positioned to engage a cap Z at its side walls, see Fig. 6. It will be noted that the ejector blade 106 in the transverse portion of the frame 107 is positioned sufficiently high above the base 36 125 to freely pass over a cap blank Y on the lower die 64 and positioning pins 71. During the movement of a cap Z by the ejector blade 106 from the cylinder 39 to the cylinder 40 its outturned flange enters the grooves 99 which 130 guides said cap into the cylinder 40 and supports the same.

From the above description it is evident that when there is no bottle under either of the capping heads the same are reciprocated by the 135 shaft 21 without causing any of their movable parts thereon to function. On the other hand, if a bottle is placed under one of the capping heads the respective head functions to form a cap and apply the same to the bottle while the 140 movable parts of the other capping head do not function.

When a bottle is placed under one of the capping heads the downward movement of said head positions the same on the bottle and is supported thereby. At the time the downward movement of the head is stopped by a positioned bottle, further downward movement of the frame 44 by the shaft 21 actuates the bell-cranks 45 and releases said frame from the head. This 150

movement of the bell-cranks 45 retracts the ejector slide 50 and the ejector blade 106 and positions the same, as shown in Fig. 4.

Continued downward movement of the frame 44 in respect to the head straightens the toggle levers 87 and 88 which projects the die 63 for cooperation with the die 64 and forms a cap from the blank thereon. The downward movement of the frame 44 in respect to the head brings the plunger 100 into engagement with the cap in the cylinder 40 and presses the same onto the positioned bottle. Further downward movement of the plunger 100 is thus arrested and becomes a base of resistance for the spring 103 and continued downward movement of the frame 44 will compress said spring 103, increase the tension thereof and more firmly force the plunger 100 onto the cap and complete the seating thereof on the bottle.

The initial return or upward movement of the frame 44 by the shaft 21 in respect to the head first buckles the toggle levers 87 and 88 which, together with the spring pressed bar 94, resets the arm 82 and thereafter the rollers 25 46 are engaged by the trip shoulders 76 which again connect the head to the frame 44 to be carried upward thereby. The initial upward movement of the head by the frame 44 operates the levers 95 which positively impart the initial return movement to the movable die 63 and release the same from the fixed die 64. At this time the die block 66 is returned to normal position by the spring 69 which lifts the formed cap from the die ring 65 and the stripper 74 removes the formed cap from the upwardly moving die 63 so that said cap loosely rests on the then elevated die block 66. The movement of the levers 45 by the upwardly moving trip shoulders 76 project the ejector slide 50 and the ejector blade 106, the former of which moves a cap blank in the cylinder 38 onto the fixed die 64 and the latter of which moves the formed cap on said die into the cap applying cylinder 40.

What we claim is:

1. In a machine of the class described, two members having an operative stroke together toward and from the bottle to be capped, one of said members adapted to abut the bottle to be capped, the other member being relatively movable with respect thereto, cap forming dies, a cap applying device, and automatic operating means set in motion by the continued movement of one of said members when the other member is halted by a bottle head in bottle capping position, to feed a cap blank to the dies, to feed a cap from the dies to the cap applying device and to cause the cap applying device to apply the cap to the bottle.

2. In a machine of the class described, a cap applying device, dies for forming a cap with a depressed central portion and an outstanding flange, means for feeding a cap blank to the dies, positioning means for centering a cap blank in respect to the dies and frictionally holding the same, and means for feeding a cap from the dies to the cap applying device simultaneously with the delivery of the blank to the dies.

3. In a machine of the class described, dies for forming a cap with a depressed central portion and an outstanding flange, a cylinder, a cap applying device in the cylinder, means for centering a bottle to be capped in respect to said cylinder, means for holding a cap centered in

the cylinder between the positioned bottle and cap applying device, and means for simultaneously feeding a cap blank to the dies and a formed cap from the dies to the cap holding means in the cylinder.

4. In a machine of the class described, a pair of cap forming dies, one of which is relatively fixed and the other of which is relatively movable, automatic means set in action by a bottle in capping position for moving the movable die into an operative position, and positive means for imparting the initial return movement to the movable die.

5. In a machine of the class described, a frame mounted for vertical movement, means for reciprocating the frame, a head movably mounted on the frame and having a cap applying device, and lock mechanism normally holding the head for common reciprocatory movement with the frame, said head adapted to be stopped on its downward stroke with said frame by engagement with the bottle head to be capped while said frame completes its stroke, said lock mechanism being adapted to automatically release the head from the frame by a movement of the frame in respect to the head when said head is in its cap applying position.

6. In a machine of the class described, a frame mounted for vertical movement, means for reciprocating the frame, a head movably mounted on the frame and having a cap applying device, and lock mechanism normally holding the head for common reciprocatory movement with the frame, said head adapted to seat down on a bottle head in capping position while said frame continues its downward stroke, said lock mechanism being adapted to automatically release the head from the frame by a movement of the frame in respect to the head when said head is in its cap applying position, and to automatically connect the head to the frame during the upward movement of the frame.

7. In a machine of the class described, a frame mounted for vertical movement, means for reciprocating the frame, a head having a cap applying device movably mounted on the frame and normally held for common reciprocatory movement therewith, said head adapted to be relatively halted on its downward stroke by the bottle head in bottle capping position, a pair of cap forming dies on the head, one of which is relatively movable, and means for operating the movable die including a bell-crank pivoted to the head, a link connecting one arm of the bell-crank to the frame and an arm on the other arm of the bell-crank and operative on the movable die, said bell-crank, link and arm being arranged to form compound toggle levers, arranged to be straightened by a downward movement of the frame when the head is in a cap applying position to move the movable die into an operative position and be straightened by the initial upward movement of the frame in respect to the head.

8. A machine for seating dished flexible sheet material plugs in bottle mouths to seal the same, embodying a holder for flat blanks; dies for forming such blanks one by one into said plugs; plug applying means for seating such plugs in bottle mouths including a receiver for formed plugs; a carrier for said holder, dies, and receiver; operating means for bringing together said carrier and a bottle for inserting plugs in the bottle mouth and for separating the carrier and the plugged bottle; means for delivering

blanks to said dies and formed plugs from said dies to said receiver; mechanisms for actuating said delivering means and said dies and plug applying means; and means to forcibly engage a bottle head present in plug receiving position to bring said mechanisms into operative relation, whereby said mechanisms remain inactive if no bottle is present in plug receiving position.

9. A machine for making and seating annularly flanged and dished plug caps in bottle mouths, embodying plug cap forming means, plug cap applying means for seating the plug cap in a bottle mouth and provided with annular means for pressing the flange of the inserted plug cap down on the top lip of the bottle mouth; means for successively delivering formed plug caps from said forming means to said applying means; mechanism for forcibly bringing together a bottle head and said applying means and for separating the same; and actuating means for said forming means and said applying means to operate the same to make a cap and to apply a cap while said bottle head and applying means are under contacting pressure engagement by the power of said mechanism and to release a completed cap and deliver the same to said applying means while said applying means and bottle head are separating.

10. A machine for making and applying caps to bottles, embodying mechanism adapted to be moved on bottle capping and return strokes, said mechanism including a cap blank holder, complementary dies for forming a blank into a cap, cap applying means, said mechanism also including a relatively movable means adapted to be halted, by the presence of a bottle in capping position, on the bottle capping stroke of said mechanism and with respect to the remainder of said mechanism, devices set in operation by the continued movement of said mechanism when said relatively movable means is halted by a bottle, to cause said dies to form a cap and to cause said cap applying means to apply a cap to said bottle, and devices brought into action on the relative return stroke of said mechanism to feed a blank from the holder to said dies and a formed cap from said dies to said cap applying means.

11. In bottle capping apparatus, in combination, a capping head movable on its capping and return strokes in cooperative relation to a bottle in capping position, and embodying a member and a carrier, said member and carrier being relatively movable when a bottle is in cooperative capping position; mechanism applied to said carrier for actuating said head on its said strokes; said head provided with shaped cap-applying means, die mechanism for forming a shaped cap from flat sheet material, means for delivering the shaped cap from said die mechanism into bottle capping relation to said applying means; and operating mechanisms between said carrier and member for actuating said die mechanism and said shaped cap delivering means, when a bottle to be capped is present in capping position and cooperating relation to said head.

12. In a bottle capping machine, in combination, a capping head having means for actuating the same on its capping and return strokes to and from cooperating relation with an abutment-constituting bottle at capping position, said head provided with cushioned yielding bottle centering and shaped cap applying means

adapted to exert downward yielding pressure on said bottle while said head is completing its capping stroke and while beginning its return stroke; a holder for flat cap blanks; die mechanism for shaping a blank into a shaped bottle cap; feed means for delivering a blank from said holder to said die mechanism; an ejector for delivering a shaped cap from the die mechanism into position for capping by said applying means; and mechanisms operative with the cooperating assistance of a bottle in capping position, to cause capping of such bottle, delivery of a shaped cap to said applying means, delivery of a blank to said die mechanism, and formation of a shaped cap by said die mechanism on a capping and return stroke of said head.

13. Bottle capping machinery including a capping head driven on its capping and return strokes and embodying a carrier and a member capable of relative movement under the abutment-constituting cooperation of a bottle in capping position with respect to said head; said head provided with and carrying a flat flexible blank magazine, die mechanism for shaping a blank into a flanged plug cap, cap applying means, a bottle head receiving and centering mouth, and devices for delivering a blank to said die mechanism and a cap from the die mechanism to the cap applying means; and means actuated by said relative movement for actuating said die mechanism and said devices.

14. In a machine for shaping and applying bottle caps; in combination; dies for contracting and shaping a flat blank into a cap having a depressed central portion and an annular outstanding top flange; means for separately feeding such blanks to said dies; a cap applying device; means for separately delivering said shaped caps from the dies to said applying device; and positioning means for centering each blank with respect to said dies including spaced upstanding members beside the dies and located at opposite sides of the center line of movement of the blanks to the dies, the distance between said members being slightly less than the diameter of said blanks but sufficient for the passage of the caps shaped from such blanks.

15. In a machine for shaping and applying bottle caps, in combination; die mechanism for producing a cap with a depressed central portion and an outstanding flange; a cylinder; a cap applying device in the cylinder; means for centering a bottle to be capped with respect to said cylinder; means for holding a cap centered in said cylinder above the bottle and below said device, said cap holding means including a pair of spaced ledges extending from said die mechanism into said cylinder, the cap flange resting on and slidably along said ledges; and cap feeding means for delivering the caps along said ledges from said die mechanism into said cylinder.

16. In a machine for shaping and applying bottle caps; a pair of cap forming dies, one of which is relatively fixed and the other relatively movable; automatic means set in action by a bottle in capping position for moving the movable die into operative relation to the other die; positive means for imparting the initial return movement to the movable die; and means whereby said automatic means after each bottle capping operation, actuates said positive means to bring about said initial return movement of the movable die.

17. In a bottle capping machine, in combination; a pair of cap forming dies, one of which is relatively fixed and the other relatively movable on its operative and return movements; 5 automatic means set in action by a bottle in capping position for moving the movable die into an operative position; positive means for imparting the initial return movement to the movable die; and a spring placed under tension 10 by the operative movement of the movable die for returning the movable die to its inoperative position.
18. In a bottle capping machine; in combination; a pair of cap forming dies, one of which is relatively fixed and the other relatively movable to and from operative and inoperative relation with respect to said fixed die; automatic means set in action by a bottle in capping position for moving the movable die into an operative position including a screw threaded connection with said movable die by which the operative stroke of said movable die in respect to the fixed die can be varied; and positive 20 means for imparting the initial return movement to the movable die.
19. In combination, in a bottle capping machine, a pair of cap forming dies, one of which is relatively fixed and the other relatively movable on its operative and return strokes; automatic means set in action by a bottle in capping position for moving the movable die on its operative stroke, including a toggle mechanism whereby said means is self-releasing with respect to the movable die on the completion of 30 its operative stroke; and means for actuating said movable die on its return stroke.
20. In combination, in a bottle capping machine; a pair of cooperating cap forming dies, one of which is relatively movable on its operative and return strokes; automatic means set in action by a bottle in capping position for moving the movable die on its operative stroke, said means being self-releasing with respect to said movable die on the completion of each 40 operative stroke thereof; means being provided for automatically resetting said automatic means with respect to said movable die; and means for actuating said movable die on its return strokes.
21. In combination, in a bottle capping machine; a frame mounted for vertical movement; 50 means for reciprocating the frame; a head movably mounted on the frame and provided with a cap applying device; lock mechanism normally holding the head to reciprocation with the frame, said head adapted to seat down on a bottle head in capping position while said frame continues its downward stroke, said lock mechanism being adapted to automatically release said head from the frame by movement 55 of the frame relatively to the head and to automatically connect the head to the frame during frame upward movement; cooperating cap forming dies relatively movable to and from operative relation; and means controlled by relative movement between the head and frame for causing operative relative die movement.
22. In a bottle capping machine, the combination of die mechanism for shaping blanks into bottle caps; a cap applying device; a reciprocating frame; means for reciprocating said frame; a capping head movably mounted with respect to said frame; lock mechanism normally holding said head to reciprocation with said frame, said head adapted to seat down on a bottle 70 in capping position while said frame continues 75 its downward stroke, said lock mechanism adapted to release said head from the frame by movement of the frame relatively to the head and to again connect the head to the frame during frame return movement; means controlled by relative movement between the frame and head for operating said die mechanism; and means actuated by said lock mechanism for feeding cap blanks to said die mechanism and caps from the die mechanism to said cap applying device.
23. In a bottle capping machine, the combination of a cap applying device; cap forming dies having operative and return relative movements; a reciprocating frame; means for reciprocating said frame; a capping head normally held to reciprocation with said frame; means whereby said head is adapted to be relatively halted by a bottle in capping position while said frame continues on its downward stroke and whereby said frame picks up said head on its return stroke; means for causing operative and return relative movements between said dies, including a bell crank pivoted to the head, a link connecting the bell crank to the frame and an operative connection from the bell crank to actuate the dies, said bell crank, link and connection forming compound toggle levers straightened by continued downward movement of the frame when the head is halted by a bottle; and positioning means actuated by the straightening of said toggle levers to impart the initial die return movement.
24. In combination, in a bottle capping machine, a cap applying device; relatively fixed and movable cap forming dies; a reciprocating frame; means for reciprocating the same; a capping head normally held to reciprocation with said frame; means whereby said head is adapted to be relatively halted by a bottle in capping position while said frame continues on its downward stroke and whereby said frame picks up said head as said frame returns on its upward stroke; means for actuating said movable die by the relative movements between the head and frame, including a bell crank and pivotal link connection between the frame and head forming a toggle, said bell crank having an operative connection with said movable die, said connection being self-releasing to limit the operative stroke of the movable die.
25. In combination, in a bottle capping machine, a cap applying device; relatively fixed and movable cap forming dies; a reciprocating frame; means for reciprocating the same; a capping head normally held to reciprocation with said frame; means whereby said head is adapted to be relatively halted by a bottle in capping position while said frame continues on its downward stroke and whereby said frame picks up said head as said frame returns on its upward stroke; means for actuating said movable die by the relative movements between the head and frame, including a bell crank and pivotal link connection between the frame and head forming a toggle, said bell crank having an operative connection with said movable die, said connection being self-releasing to limit the operative stroke of the movable die, said connection being also adjustable to vary the operative stroke of the movable die with respect to its cooperating die.
